UNITED STATES PATENT OFFICE.

LOUIS J. COBLENTZ, OF NEW YORK, N. Y., ASSIGNOR TO LEON WEIL, INC., OF NEW YORK, N. Y., A CORPORATION OF NEW YORK.

DESIGN FOR A SHOE ORNAMENT OR ARTICLE OF SIMILAR NATURE.

Application filed December 7, 1925. Serial No. 15,677. Term of patent 3½ years.

To all whom it may concern:

Be it known that I, LOUIS J. COBLENTZ, a citizen of the Republic of France, residing at New York city, in the county and State of New York, have invented a new, original, and ornamental Design for Shoe Ornament or Article of Similar Nature, of which the following is a specification, reference being had to the accompanying drawing, forming part thereof.

In the said drawing:

Fig. 1 is a front view of a shoe ornament or article of similar nature, showing my new design; and

Fig. 2 is an edge view thereof.

I claim:

The ornamental design for a shoe ornament or article of similar nature, as shown.

LOUIS J. COBLENTZ.
